UNITED STATES PATENT OFFICE.

JOHN S. METCALF, OF CHICAGO, ILLINOIS, ASSIGNOR TO JOHN S. METCALF COMPANY, OF CHICAGO, ILLINOIS, A CORPORATION OF ILLINOIS.

METHOD OF ERECTING METAL-CONCRETE STRUCTURES.

SPECIFICATION forming part of Letters Patent No. 789,988, dated May 16, 1905.

Application filed August 8, 1904. Serial No. 219,918.

To all whom it may concern:

Be it known that I, JOHN S. METCALF, a citizen of the United States, residing at Evans-
ton, in the county of Cook and State of Illi-
nois, have invented a new and useful Improve-
ment in Methods of Erecting Metal-Concrete
Structures, of which the following is a speci-
fication.

My invention relates to an improved method
of erecting the class of buildings the walls of
which are composed of concrete molded in
sections about vertical and horizontal metal
bars to embed them for their reinforcing ef-
fect. The common practice observed in erect-
ing structures of the kind referred to is to lay
the foundation and form upon it the walls in
sections, employing for the purpose suitable
outside and inside mold-sections, between
which the concrete is molded about the pre-
parately-placed metal reinforcing-bars; and
when a section thus formed has been allowed
to set for a sufficiently long period the mold
is removed and the same or another mold is
adjusted on the previously-finished section to
receive another filling of concrete, requiring
to be hardened by setting before the mold is
removed to be readjusted for filling in an-
other section. Thus forming the wall of the
structure section after section incurs waste of
time in waiting for each previous section to
set and in the removal or readjustment, or
both, of the mold, with the result of delay in
the erection and attendant expense for labor.

The primary object of my improvement is
to avoid this waste of time, with the advantage
of expediting the work and greatly reducing
the expense of erection by enabling the work
to be performed continuously. This I ac-
complish by raising the mold from under-
neath as the work proceeds either continu-
ously or intermittently without removing or
readjusting it, and therefore without require-
ment for its repeated disintegration and rein-
tegration, and for practicing my improve-
ment suitable mechanism is illustrated in the
accompanying drawing in position upon a
metal-concrete wall undergoing erection, the

showing being by a view in vertical sectional
elevation.

A is the outer section of a circular mold, 50
and B is the inner section thereof, for a cy-
lindrical structure, though, as will be under-
stood, their shape may be varied to accord with
that of walls to be erected of cross-sectional
shape other than cylindrical. The nature of 55
the view selected for illustration is not such
as to enable the cylindrical form of the struc-
ture to be represented, but that form may be
readily understood to facilitate the explana-
tion of my invention. At suitable intervals 60
about the mold, which may involve any suit-
able construction, frames C rise vertically
from it, these frames comprising beams a on
the outer mold-section and coincident there-
with similar beams on the inner mold-section, 65
with spacing-beams c rising from between the
beams a and b, these several beams being fas-
tened together by bolts d passing transversely
through them. The beams c serve to space
apart the mold-sections and are of a thickness 70
according to the thickness of the wall D to
be formed in the mold by filling concrete
into it and embedding therein vertical metal
bars e, placed at suitable intervals apart, and
circuitous metal bars f, intersecting the bars e 75
at desired intervals. The beams c about the
mold may be connected together from one to
the other at their upper ends by strips g,
through which the bars e pass for guidance in
setting them and for retaining them in their 80
proper relative positions. E denotes scaf-
folding within the plane of the inner mold-
section and on which the mold is supported
to be carried by raising the scaffolding, as and
for the purpose hereinafter described. As 85
shown, the scaffolding comprises an outer
section formed of legs h, preferably corre-
sponding in number with that of the frames
C, and an inner central section formed of
similar legs h' in desired number connected 90
together at intervals along their height by
cross-bars i, this central section being con-
nected at intervals along its legs by cross-
bars k with the legs h of the outer section of

the scaffolding, and floor-beams *l* extend from the frames *C* to the central section of the scaffolding and support flooring *m* for the working floor. Thus the mold and scaffolding are 5 rigidly tied together.

In erecting a metal-concrete structure with the use of the mold carried by the inside, outer, and central scaffolding *E* the mold is raised as the molding work progresses by 10 raising the scaffolding with power applied underneath it, preferably through the medium of jack-screws *F*, of usual or suitable construction, the operation being performed as follows: To start the erection of a wall *D* 15 upon a preparatorily-formed foundation the line of which is indicated at *n*, the mold with the initially-constructed portion of the scaffolding *E*, being that portion of the scaffolding illustrated which is within the confines of 20 the mold, with the framework *C* extending above the latter, is placed in position upon the foundation. Jack-screws are placed to rest at their bases upon the foundation, one underneath each beam *l* near its junction with 25 the inner mold-section. If the height of the mold is greater than the length of jack employed, as it ordinarily is, each jack may be blocked from underneath in a well-known manner to cause it to bear at its upper end 30 against the respective beam. With the vertical metal bars *e* placed at proper intervals between the mold-sections and supported in position by passing through the strips *g* concrete is filled into the mold to begin the wall 35 *D* and at proper intervals (of, say, three feet) the horizontal intersecting metal bars *f* are placed and embedded in the concrete filling. As the wall grows in height within the mold 40 laborers turn the jack-screws to raise the scaffolding, and with it the mold, along the wall-surfaces, thereby incidentally smoothening them. When by continuously filling concrete into the mold-space and meantime raising the mold by turning the jack-screws the height 45 to which the mold is raised enables strips *h* in predetermined length—say of seven feet, more or less—to form sections of the scaffolding-legs *h* *h*', to be bolted thereto to extend at their lower ends short of the foundation- 50 surface sufficiently to admit the jack-screws underneath them, the first of these extension-sections of the scaffolding-legs are thus applied. The jack-screws are reset from time to time as required (removing for the re-setting purpose only a few at a time, so as to leave the others in place for stably supporting the mold and scaffolding structure) underneath the legs of the scaffolding, and as the 55 work of concrete filling into the mold about the metal reinforcing-bars progresses the jack-screws are turned to further raise the mold. When a jack-screw becomes extended to its full capacity under a scaffolding-leg—say to the height of eighteen inches—

it may be blocked underneath from time to 65 time or otherwise raised to cause it to continue to perform its raising function until its base becomes elevated above the surface of the foundation sufficiently to admit the jack-screw underneath another length of leg-section *h* *h*', when such a strip is added and the jack-screw is adjusted underneath it. The work of thus raising the scaffolding, and with it the mold, by turning the jack-screws may be performed in the erection of a large-sized structure by, say, two laborers during the day 70 while the filling with concrete is in progress and by one laborer during the night while the filling work is suspended, these laborers attending to the adjustment of the jack-screws as required. The mold-raising operation continues until the desired height of wall is attained, when it is dismantled of the mold and scaffolding. The mold-raising operation may be performed intermittently or continuously 75 while the mold is being filled, and though jack-screws placed underneath the scaffolding and worked by hand-labor have proved perfectly satisfactory means for practicing my invention it is feasible to employ other power 80 for turning the jack-screws and means other than jack-screws applied from underneath the scaffolding and operated by power other than hand-labor, continuously or intermittently, for raising the mold. It will readily be seen that 85 by thus raising the mold as the erection of the structure progresses interruption for dismantling and readjusting molds, with incidental delays due to waiting for the concrete to set, 90 are avoided and the progress of erection rendered continuous, with the advantage of great saving in time and expense and that of smoothening the wall-surfaces by the rise in contact with them of the mold, thereby avoiding the usual requirement in connection with molded 95 concrete walls of going over them for smoothening and finishing after the work of erection is completed.

What I claim as new, and desire to secure by Letters Patent, is—

1. In erecting the wall of a structure of the character described by filling concrete into a mold, the method of rendering continuous the progress of erection, which consists in raising the mold from underneath the same along the 100 surfaces of its filling of concrete while the filling work is proceeding.

2. In erecting the wall of a structure of the character described by filling concrete into a mold supported on scaffolding inside the structure, the method of rendering continuous the progress of erection which consists in raising the scaffolding from underneath the same, and with it the mold along the surfaces of its filling of concrete while the filling work is proceeding.

3. In erecting the wall of a structure of the character described by filling concrete into a

mold, the method of rendering continuous the progress of erection, which consists in jacking the mold from underneath the same to raise it along the surfaces of its filling of concrete while the filling work is proceeding.

4. In erecting the wall of a structure of the character described by filling concrete into a mold supported on scaffolding inside the structure, the method of rendering continuous the

progress of erection, which consists in jacking ^{to} the scaffolding from underneath the same to raise it and with it the mold along the surfaces of its filling of concrete while the filling work is proceeding.

JOHN S. METCALF.
